FRAME FOR SUPPORTING AN ADVERTISING DISPLAY OR THE LIKE

Sheldon C. Brooks, Minneapolis, Minn.

Application January 6, 1958, Serial No. 49,156

Term of patent 7 years

(Cl. D80—1)

FIG. 1

FIG. 2

FIG. 3

Figure 1 is a perspective view of a frame for supporting an advertising display or the like on a reduced scale showing my new design, the line shading representing a contrast in color.

The broken line showing in Figures 1, 2 and 4 is for illustrative purposes only.

I claim:

The ornamental design for a frame for supporting an advertising display or the like, as shown and described.
